(57) **CLAIM**

The ornamental design for a handbag, as shown and described.

DESCRIPTION

FIG. 1 is a front perspective view of the handbag showing our new design in an open position;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of the handbag showing our new design in a closed position;

FIG. 9 is a front elevation view thereof showing the handbag in a closed position;

FIG. 10 is a rear elevation view thereof showing the handbag in a closed position;

FIG. 11 is a left side elevation view thereof showing the handbag in a closed position;

FIG. 12 is a right side elevation view thereof showing the handbag in a closed position;

FIG. 13 is a top plan view thereof showing the handbag in a closed position; and,

FIG. 14 is a bottom plan view thereof showing the handbag in a closed position.

The broken lines representing stitching are part of the claimed design.
